UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

1,419,648.

Specification of Letters Patent. Patented June 13, 1922.

Application filed February 2, 1920. Serial No. 355,591.

To all whom it may concern:

Be it known that I, JESSE A. B. SMITH, a citizen of the United States, residing in Stamford, in the county of Fairfield and 5 State of Connecticut, have invented certain new and useful Improvements in Type-writing Machines, of which the following is a specification.

This invention relates to typewriting machines, and is herein disclosed as applied to an Underwood standard typewriting machine of the general sort shown in the patent to Wernery & Smith, No. 1,132,055, dated March 16, 1915, in which the platen 10 is adapted to be lifted in the carriage to permit work-webs to be drawn substantially straight forward beneath it to enable them to be gaged.

In such machines, as in other typewriting machines, one of the urgent problems has been that of securing registration of superposed work-webs, especially when such webs have forms printed upon them which are to be filled out in the course of the typewriting. Part of the difficulty in aligning work-webs arises from the fact that superposed work-sheets creep, in passing around the platen, the outer upon the inner, and this creeping is cumulative in the case of 15 work-sheets which are in the form of continuous webs.

According to the present invention, gaging or aligning of superposed work-webs may be effected by follower pins or similar 20 devices, preferably tapering, adapted to enter perforations similarly placed in the forms on the superposed webs on which they normally rest, with the result that when the pins or devices are fully entered into the 25 perforations, the superposed webs are realigned or brought into registration and are also gaged by the pins or devices. It will be seen that the pins act as feelers or penetrating members to co-operate with 30 the perforations.

In a machine of the Wernery & Smith kind referred to, the pins or devices may advantageously be mounted on a bar which is on the rearward extension of the typewriter 35 carriage, and to enable ready adjustment of the pins to work-forms of different lengths or to differently locate perforations, the bar carrying the pin or pins may be shiftable with the stop which is usually 40 included in such machines and serves to

limit the rearward motion of the carbon-paper-carriage. The connections may be such that the pin or pins normally bear upon the surface of the web, but not with sufficient friction to prevent the advance of 45 the web by the line-spacing mechanism if desired. The connections may include a spring which drives the pin or pins through the perforations when the perforations reach the pin or pins. The pin or pins 50 will be supported when in contact with an imperforate portion of the work-sheet, but will pass through a web or webs when an opening or openings register therewith. To release the webs from the pins, the carbon-paper-carriage may be provided with a cam or device which is adapted to lift the pins 55 clear of the webs, thus permitting the webs to be drawn forward so that the perforations are clear of the path of the pins. 60

When the device is used in this manner, the usual leading-edge gage for the webs may be omitted, and when the platen is drawn upward to permit the webs to be drawn forward, the typist may pull the 65 webs forward slowly in the usual manner until they are arrested by the entering of the pin into the perforations, thus gaging them. The pushing of the carbon-paper-carriage rearwardly may release the webs 70 from the pin at this time, and thus permit the work to be further drawn upon if desired. Other features and advantages will hereinafter appear. 75

In the accompanying drawings, 90
Figure 1 is a diagrammatic sectional side view of a machine of the kind referred to, showing a pin riding upon the surface of the web.

Figure 2 is a similar view, showing the 95 platen swung up and the webs drawn forward until gaged by the pins entering the perforations.

Figure 3 is a view similar to Figure 2, but showing the carbon-paper-carriage pushed 100 rearwardly to lift the pins and release the webs.

Figure 4 is a fragmentary perspective view of the pins, their mounting, and some adjacent parts. 105

In the Underwood standard typewriting machine of the general kind shown in said patent to Wernery & Smith, a plurality of webs or sheets 10, 11 and 12 are drawn from the rear over a back rod 13, forming part of 110

an extension 14 of the typewriter carriage 15, and are carried forwardly under the platen 16 past the feed-rolls 17 and 18, so that types 19 upon type-bars 20 may print 5 upon the webs through a ribbon 21. The types 19 print not only upon the outside web 12, but also upon the inside webs 10 and 11, because sheets of carbon paper 22 and 23, fast to the usual clip bars 24 and 25 of the 10 carbon-paper-carriage 26, extend forwardly around the platen and up past the printing point at the ribbon 21.

When a work-form upon the webs 10, 11 and 12 has been typed in the usual manner, 15 the platen is released by swinging rearwardly the hook 27 which normally overlies a pin 28 upon the swing frame 29 in which the platen is mounted, thus permitting the platen to be swung upwardly to the Figure 20 2 position, by lifting the frame 29 to swing it around its pivot 30 at the front of the carriage 15. When the platen 16 is in the Figure 2 or Figure 3 position, the webs 10, 11 and 12 may be seized by the typist at 25 their forward ends and drawn forward until arrested by a follower pin or pins 31, which are herein shown as mounted upon a cross-bar or bail 32 forming a pin frame having forwardly-extending arms 33 pivoted at 34 30 on a stop 35, which, in some respects, resembles the usual stop for the carbon-paper-carriage in such machines. The pin 31 arrests the webs 10, 11 and 12, because it is provided with a tapered end 36, having a 35 flat or rounded tip 37 which rides upon the web, but which, when a perforation 38 in any of the webs comes adjacent the pin, enters therein because the pin is pressed against the web by a spring 39 secured to the 40 stop 35.

To enable the pin or pins 31 to be effective in this manner, the stop 35 comprises a cross-bar 40 connecting the slides 41, which ride upon the rails 42 upon which the carbon-paper-carriage 26 travels. The pins 31 are enabled to align the webs 10, 11 and 12 in the manner described, because the cross-bar 40 is provided with sockets or openings 43, into which the pins 31 are adapted to 45 enter in passing through the perforations, while the webs are supported upon the cross-bar 40. This enables the tapering sides 36 of the pins to align the webs before the cross-bar 32 comes down flat upon the cross-bar 40. The arms 33 advantageously have their pivots 34 considerably to the rear of the pins 31, thus giving the pins a comparatively flat arc of swing.

When the work-webs have been drawn 60 forward until arrested, as at the Figure 2 position, the typist pushes rearwardly the carbon-paper-carriage 26 by its usual forwardly-extending handle or finger-piece 44 to the Figure 3 position, meantime grasping 65 the ends of the webs 10, 11 and 12 against

the usual upper extension 45 of the front paper-table 46. This holds the webs firmly in position while the pins 31 are lifted clear of the work-webs 10, 11 and 12 by the striking of a cam 47 against a lever arm forming 70 a forward cam extension 48 of one of the arms 33, at one side of the carriage extension 14. If at any time found desirable, the lever arm 48 may be employed as a finger-piece or handle for manually lifting the 75 pins 31 to release the webs therefrom. The cam 47 is mounted upon one side of the carbon-paper-carriage 26, and may be held thereto by screws 47a. In this Figure 3 position, the cam 47 has lifted the pins 31 80 clear of the webs 10, 11 and 12, with the result that when the platen 16 is swung back to the Figure 1 position, the bending of the webs downwardly over the rear paper-table 49 and beneath the platen creates a 85 bend in them, thus dragging the carbon-paper-carriage 26 forward because of the friction of the carbon sheets upon the web. This releases the pins 31; the length of the cams 47 and 48 is, however, so adjusted that 90 the moving of the carbon-paper-carriage forward by this returning of the platen does not release the pins until the perforations 38 beneath the pins have been drawn forward clear of the pins, with the result 95 that the pins ride upon the surface of the outer web, as shown in Figure 1. The typist then usually detaches the section of web which has been already written upon, by drawing it against the usual knife 50, 100 and then advances (or returns) the webs to the proper typing position, which may be the Figure 1 position. To enable the stop 35 to be adjusted to suit the work in hand, it is provided with a clamp 51 adapted to 105 seize the adjacent rail 42.

To keep the webs in edgewise alignment, the rear rod 13 may include the usual adjustable side gages 52, and the carbon-paper-carriage may also include the usual side 110 gages, not shown. If desired, there may be provided a separate cam extension 48 for each end of the bar 32, as shown in Figure 4. In order to enable the cams 47 and 48 to co-operate properly in holding the pins 115 31 clear of the webs while the platen is being returned, the cam 47 may include a considerable dwell 53. The spring 39 is advantageously a flat spring overlying one arm 33, thus minimizing the liability of its being entangled with the webs 10, 11 and 12.

Variations may be resorted to within the scope of the invention, and portions of the improvements may be used without others.

Having thus described my invention, I 125 claim:

1. In a typewriting machine, the combination with a traveling carriage and a revoluble platen therein, of a device past which work-sheets are drawn in passing 130

around the platen, a pin forming part of said device, and a spring adapted to press said pin upon the surface of the work-sheets and to cause it to enter perforations in 5 superposed work-sheets to align them by bringing the perforations to register.

2. In a typewriting machine, the combination with a traveling carriage, of a revoluble platen therein, a swing frame in 10 which the platen is mounted to enable the platen to be lifted upward, to enable work-webs to be drawn forward substantially straight beneath it, a rear extension of the carriage over which the webs are so drawn, 15 a pin upon said extension, and means for pressing upon said pin to cause it to enter perforations in superposed work-webs to align them by bringing their perforations to register.

20 3. In a typewriting machine, the combination with a traveling carriage, of a revoluble platen therein, a swing frame in which the platen is mounted to enable the platen to be lifted upward, to enable work-webs to be drawn forward substantially 25 straight beneath it, a rear extension of the carriage over which the webs are so drawn, a pin adjustably mounted upon the extension, and a spring normally causing the pin to bear upon the surface of a web, and adapted to cause it to enter perforations in superposed webs to align them by bringing their perforations to register.

4. In a typewriting machine, the combination with a traveling carriage, of a revoluble platen therein, a swing frame in 35 which the platen is mounted to enable the platen to be lifted upward, to enable work-webs to be drawn forward substantially straight beneath it, a rear extension of the carriage over which the webs are so drawn, a pin mounted to swing upon said extension, a spring normally swinging the pin against a web drawn over the extension, and adapted 40 to cause it to enter perforations in superposed webs to bring their perforations into register to align the webs, and connections including a finger-piece or handle extending toward the front of the carriage to move the pin clear of the webs.

50 5. In a typewriting machine, the combination with a traveling carriage, of a revoluble platen therein, a swing frame in which the platen is mounted to enable the platen to be lifted upward, to enable work-webs to be drawn forward substantially 55 straight beneath it, a rear extension of the carriage, a carbon-paper-carriage slidable on said extension, a stop for the carbon-paper-carriage adapted to limit its rearward movement, pins mounted to swing upon the extension and normally bearing upon the surface of a web drawn over the extension, and adapted to enter perforations in superposed webs to bring them to register, and means 60 made effective by movement of the carbon-

paper-carriage for moving the pins clear of the webs.

6. In a typewriting machine, the combination with a traveling carriage, of a revoluble platen therein, a swing frame in 70 which the platen is mounted to enable the platen to be lifted upward, to enable work-webs to be drawn forward substantially straight beneath it, a rear extension of the carriage, a carbon-paper-carriage slidable on 75 said extension, an adjustable stop for limiting the rearward movement of the carbon-paper-carriage, a frame comprising pins adapted to swing upon the stop, a spring normally holding the pins against the surface of a web, and adapted to cause the pins to enter perforations in superposed webs to bring them to register, a cam arm connected to said pin frame, and a cam on the carbon-paper-carriage adapted to operate said cam 80 arm to lift the pins clear of the webs.

7. In a typewriting machine, the combination with a traveling carriage, and a revoluble platen therein, of feed rolls adapted to bear upon webs passed around the platen, 90 means for effecting separation between the platen and feed rolls, a swinging member behind the platen, and a pin on said member adapted to be carried into perforations on superposed webs to align them when the 95 platen and rolls are separated, and adapted to be held clear of the webs.

8. In a typewriting machine, the combination with a traveling carriage, and a revoluble platen therein, of feed rolls adapted 100 to bear upon webs passed around the platen, means for effecting separation between the platen and feed rolls, a paper-table behind the platen, a swinging member behind the paper-table, pins on said member adapted 105 to be carried into perforations on superposed webs to align them, and a manually-operated cam adapted to hold the pins clear of the webs.

9. In a typewriting machine, the combination with a traveling carriage, of a revoluble platen therein, a swing frame in which the platen is mounted to enable the platen to be lifted upward, to enable work-webs to be drawn forward substantially 110 straight beneath it, a rear extension of the carriage over which the webs are so drawn, and spring-pressed pins upon the extension normally bearing upon a web and adapted to enter perforations in superposed webs to 115 gage the webs and to align them.

10. In a typewriting machine, the combination with a traveling carriage, of a revoluble platen therein, a swing frame in which the platen is mounted to enable the platen to be lifted upward, to enable work-webs to be drawn forward substantially straight beneath it, a rear extension of the carriage over which the webs are so drawn, a knife adjacent the printing line upon the 125 platen, and pins upon the extension adapted 130

to enter perforations in superposed webs to gage them for the knife and align them.

11. In a typewriting machine, the combination with a traveling carriage, of a 5 revoluble platen therein, a swing frame in which the platen is mounted to enable the platen to be lifted upward, to enable work-webs to be drawn forward substantially straight beneath it, a rear extension of the 10 carriage over which the webs are so drawn, a knife adjacent the printing line upon the platen, pins upon the extension adapted to enter perforations in superposed webs to gage them for the knife and align them, resilient means normally holding the pins upon the webs, and a manually-operable device adapted to raise the pins clear of the webs.

12. In a typewriting machine, the combination with a traveling carriage, of a 20 revoluble platen therein, a swing frame in which the platen is mounted to enable the platen to be lifted upward, to enable work-webs to be drawn forward substantially straight beneath it, a rear extension of the 25 carriage over which the webs are so drawn, a knife adjacent the printing line upon the platen, a carbon-paper-carriage running upon the extension and adapted to have carbon sheets clipped to it, a rear stop for the 30 carbon-paper-carriage adapted to arrest it with the carbon sheets clear of the knife, a pin frame swingable upon the stop and comprising pins adapted to enter perforations in superposed webs to align them, a spring 35 normally tending to make the pin frame effective, and a cam upon the carbon-paper-carriage adapted to set it to ineffective position at the rearmost position of the carbon-paper-carriage.

40 13. In a typewriting machine, the combination with a traveling carriage, of a revoluble platen therein, a swing frame in which the platen is mounted to enable the platen to be lifted upward, to enable work-webs to be drawn forward substantially straight beneath it, a rear extension of the 45 carriage over which the webs are so drawn, a pin upon said extension, means for pressing upon said pin to cause it to enter perforations in superposed work webs to align them by bringing their perforations to register, and a manually-operated cam adapted to make the pin ineffective, the connections being such that when the platen is dropped 50 the webs are advanced, the cam becomes ineffective and the pin rides upon the surface of the outer web.

14. In a typewriting machine, the combination with a traveling carriage, of a 60 revoluble platen therein, a swing frame in which the platen is mounted to enable the platen to be lifted upward, to enable work webs to be drawn forward substantially straight beneath it, a rear extension of the 65 carriage over which the webs are so drawn,

a pin upon said extension, means for pressing upon said pin to cause it to enter perforations in superposed work webs to align them by bringing their perforations to register, a carbon-paper-carriage riding upon the extension, a rear stop for said carbon-paper-carriage, a swinging arm on said stop carrying said pin, a cam extension of said arm at one side of the carriage extension, and a cam on the carbon-paper-carriage 75 adapted to operate the cam extension to make the pin ineffective.

15. In a typewriting machine, the combination with a traveling carriage comprising a platen, of an extension of said carriage 80 behind the platen, a bar pivoted to swing on said extension, a co-operating bar, and a plurality of tapered pins on said pivoted bar adapted to pass through perforations in a plurality of work-webs and enter sockets 85 in the co-operating bar to align the webs.

16. In a typewriting machine, the combination with a traveling carriage comprising a platen, of an extension of said carriage behind the platen, a bar pivoted to swing on 90 said extension, a co-operating bar, a plurality of tapered pins on said pivoted bar adapted to pass through perforations in a plurality of work-webs and enter sockets in the co-operating bar to align the webs, a device 95 normally pressing the pins toward effective position during writing, and means for releasing the webs to enable a fresh length to be brought to the platen.

17. In a typewriting machine, the combination with a platen, of work-sheet-positioning means comprising a work-sheet support having an opening therein, a follower to rest on a work-sheet on said support, the follower engaging a portion of the work-sheet extending across said opening, and means including a spring to urge the follower against the work-sheet, the spring being so feeble that it may be overcome by a portion of the work-sheet extending across 105 the opening, whereby, upon movement of the work-sheet to bring an opening therein opposite the follower, the latter will pass through said opening and hold the work-sheet against further movement. 110

18. A sheet-positioning device for a typewriting machine having a platen, said device comprising members, one having a projection thereon and the other having an opening therein to receive said projection, and a spring to urge said members toward each other, the spring being so feeble that a work-sheet on said platen and interposed between said members may prevent said projection from entering said opening, whereby, upon shifting the work-sheet to bring a properly positioned opening therein opposite the projection, the latter will pass through the opening in the work-sheet and into the opening in the member on the other 125 130

side of the work-sheet, thereby holding the latter against movement.

19. A sheet-positioning device for a type-writing machine having a platen, said device comprising a pair of bars extending substantially parallel with the platen and relatively spring-pressed toward each other and toward a work-sheet which may be drawn between said bars, a socket being provided 5 in one of said bars, and a pin carried by the other said bar to enter said socket, the work-sheet having a perforation therein positioned to register with said socket as the work-sheet is drawn along so that said pin 10 will ride on the work-sheet and will enter the perforation therein to bring the work-sheet to a stop at the desired position.
20. A sheet-positioning device for a type-writing machine having a platen, said de-

vice comprising a pair of bars extending 20 substantially parallel with the platen and relatively spring-pressed toward each other and toward a work-sheet which may be drawn between said bars, a socket being provided in one of said bars, a pin carried by 25 the other said bar to enter said socket, the work-sheet having a perforation therein positioned to register with said socket as the work-sheet is drawn along so that said pin 30 will ride on the work-sheet and will enter the perforation therein to bring the work-sheet to a stop at the desired position, and means for releasing the work-sheet from said pin.
